UNITED STATES PATENT OFFICE.

WERDEN A. SANDERS, OF PORTLAND, OREGON.

WINDOW-SCREEN.

1,127,289.

Specification of Letters Patent.

Patented Feb. 2, 1915.

Application filed February 18, 1914. Serial No. 819,449.

To all whom it may concern:

Be it known that I, WERDEN A. SANDERS, a citizen of the United States, residing at Portland, in the county of Multnomah and State of Oregon, have invented new and useful Improvements in Window-Screens, of which the following is a specification.

This invention relates to window screens and has particular reference to screens capable of lateral adjustment so as to accommodate window casings of varying width, and also adapted to be raised and lowered in suitable tracks provided therefor.

The primary object of the invention is the provision of a screen wherein the side members of the frame are composed of an inner stationary section and an outer laterally movable telescopic section, which are normally held yieldably extended in effective engagement with the tracks secured on the window frame, and serves to equalize any irregularities in the window frame.

In carrying out my invention, it is also my purpose to provide means for locking the screens in their normal position or in any desired vertical adjusted position.

I further aim to provide a screen including a frame constructed preferably of metal and so formed as to provide a tight joint between the adjacent rails of the upper and lower screens when the latter are normally disposed.

Another object of the invention is to provide a screen of the above mentioned character which may be readily and easily applied to or removed from a window frame when desired.

Other objects and advantages will appear from the following description of the invention, the latter residing in the specific construction, combination and arrangement of parts hereinafter more fully described.

A practical embodiment of the invention is shown in the drawings forming a part of this application, and in which like numerals of reference indicate similar parts in the several views.

Figure 1 is a front elevation of my improved screen in use. Fig. 2 is a horizontal sectional view taken on line 2—2 of Fig. 1. Fig. 3 is an enlarged vertical sectional view of the side members of the screen frame. Fig. 4 is an enlarged sectional view taken on line 4—4 of Fig. 3. Fig. 5 is a similar view showing the cam in inoperative position, and the manner of removing

the screen. Fig. 6 is a sectional view taken on line 6—6 of Fig. 1. Fig. 7 is a similar view taken on line 7—7 of Fig. 1. Fig. 8 is a detail section of a modified form. 60

Referring more particularly to the drawings A designates the window casing provided with the usual blind stop B to which are secured in any suitable manner the tracks 5, which extend throughout the entire length of the stop and upon which the screens are adapted for slidable adjustment. In the preferred embodiment of the invention, the tracks are of substantially U-form and are permanently secured to the blind 65 stops B in the manner shown. The side members 8 and 9 of the tracks are adapted to slidably receive the upper and lower screen 10 and 11 respectively, whereby the latter may be raised and lowered to any desired adjusted position. The upper and lower screens are similarly constructed with the exception of the adjacent or meeting rails thereof which are especially formed 70 to provide a tight joint therebetween when the screens are normally disposed and which will hereafter be more fully described. 75

Each screen comprises a sheet of suitable foraminous material and a frame which may be constructed from any suitable material, 80 preferably metal. The side rails 12 of each screen comprise inner and outer telescopic sections 13 and 14 respectively. The outer sections 14 are formed from a single sheet 85 of metal and comprise a short wall 15 and a relatively long wall 16 disposed in parallelism with the said short wall and connected therewith by the end walls 17. The end walls 17 are formed to provide inwardly 90 disposed channels 18 which slidably receive the side members 8 and 9 respectively of the tracks 5 for the purpose hereinabove set forth. The inner sections 13 which are also formed from a single sheet of metal 95 which is bent to provide spaced parallel walls 19 and 20 defining a channel by the intervening space therebetween in which the said short wall 15 of the outer section is slidably mounted, thus permitting the outer section to telescope within the said 100 inner section. The walls 20 are bent at their outer edge as at 21 and are extended inwardly to provide a wall 22 disposed in spaced parallelism with the wall 20, and as shown the marginal edge of the forami- 105 nous material is effectively clamped between these walls. The inner edge of the wall 22

110

is bent upon itself to provide an outwardly extending flange 23 against which is adapted to abut the inwardly extending flange 24 formed by bending the free edges of the 5 wall 16, the latter serving in the capacity of a stop to limit the movement of the outer section in one direction, on relative lateral extension of the latter.

The upper rail 25 of the upper screen and 10 the lower rail 26 of the lower screen are similarly constructed as clearly indicated in Fig. 7. These rails are constructed from a single sheet of metal into substantially U-form between the parallel walls 27 and 28 of which the marginal edges of the foraminous material are suitably secured.

The outer wall 28 of each rail is bent adjacent its upper and lower edges to form 20 spaced reinforcing beads which extend across the entire width of the rail, and these beads serve as finger holds for raising and lowering the screens.

The upper rail 29 of the lower screen is 25 of substantially inverted U-shaped formation, and between the walls of which the upper marginal edge of the foraminous material is secured in any suitable manner.

The outer wall 30 of the rails is formed 30 with a reinforcing bead 31 adjacent its lower edge.

The lower rail of the upper screen comprises an inner member 32 and an outer member 33 between which the foraminous material is clamped by suitable fastening 35 elements 34 retaining the members connected. The inner member 32 is formed adjacent its upper edge with an inwardly disposed reinforcing bead 35, while the outer member 33 terminates at its lower edge to provide an inwardly extending bulged portion 36 adapted to normally contact the wall 37 of the rail 29 to form a tight joint between the parts when the screens are normally disposed.

With a view of normally retaining the said telescopic sections yieldably extended and to effectively hold the screens in snug engagement with the tracks, I employ a bowed spring 38 arranged between the sections and extending throughout approximately the entire length thereof. The spring has its free ends bearing against the end wall 17 of the outer section 14 adjacent the upper and lower edges thereof, while the intermediate portion of the spring bears against the flange 23 of the inner section 13. By reason of this arrangement, it is manifest that the spring not only operates to normally retain the sections yieldably extended, but further serves to equalize any irregularities in the window frame.

With the structure hereinabove described, I employ a locking means for locking the screens in either their normal position or in 65 any desired vertical adjusted position. This

means as shown in one embodiment of the invention consists of pins 39 mounted for rotation in the walls 20 and 22 of the inner section 14, and each pin carries at its forward end a cam 40 which cams are adapted when in operative position to bear against the walls 41 of the channels 18, thus serving to hold the screen immovably positioned in the window frame. The forward ends of the pins are provided with slots 42 for the reception of a suitable key for rotating the pins to move the cams into operative or inoperative position.

The front walls 16 of the outer sections are provided with suitable openings to permit the key to be inserted therethrough into engagement with the pins. As will be noted the cams are so arranged that the screens will be effectively locked at each of the four corners thereof.

In Fig. 8 I have shown the track yieldably supported, which is adapted for use with screens of the above indicated construction, with the exception of the fact that the locking cams 39 are omitted. In this form of the 90 invention the track 42 which is U-shaped in formation is connected with a yieldable supported plate 43. The plate is substantially L-shaped, the portion 44 of which slidably engages the outer surface of the blind stop 95 B, and is connected therewith by means of a fastening element 45 in the manner shown. A spring 46 encircles the element 45 and is interposed between the blind stop B and the portion 47 of the supporting plate, and operates to yieldably support the track 42^a in spaced relation to the window frame. Manifestly by reason of this construction and arrangement the track 42^a exerts an inward pressure against the screen while the telescopic sections of the latter exert an outward pressure against the track, and thus the screens are effectively held in normal position or in any desired adjusted position without the use of the locking cams 40.

It will be further obvious that the application of screens, constructed in accordance with my invention, to a window frame and their removal therefrom is greatly facilitated.

From the foregoing description considered in connection with the accompanying drawings it is believed that the nature and advantages of the invention will be thoroughly understood, and while I have shown what I now consider a practical embodiment of the invention, the same is merely illustrative, it being desired to have it understood that various changes in the construction and arrangement of parts may be made within the scope of the appended claims.

What I claim is:—

1. In combination, an upper and lower vertically adjustable screen including metallic frames, the lower and upper rail of the 130

respective screens being substantially U-shaped and provided with laterally disposed reinforcing beads, said lower rail being formed with an inwardly disposed bulged portion for contact with said upper rail to form a tight joint between the parts.

2. In a window screen, a frame, the side members of said frame comprising laterally movable telescopic sections, means for normally extending said sections, and coöperating flanges formed on the sections for contact with each other to limit the movement of the telescopic sections in one direction.

3. In a window screen, a frame including laterally movable telescopic sections, means for yieldingly supporting said sections normally extended, and means for locking the sections in said extended position.

4. In a window screen, a frame including laterally movable telescopic sections, means for yieldingly supporting said sections nor-

mally extended, means for locking the sections in said extended position, said means comprising cams mounted for rotation between said sections and adapted to bear against the side wall of one of said sections in operative position.

5. A track for window screens comprising an L-shaped plate, a substantially U-shaped track member mounted on the short arm of said plate, an element fastened on the window frame and adapted to slidably receive the short arm of said plate and said track, and a spring interposed between the frame and said short arm of the plate for yieldingly supporting said track for horizontal movement.

In testimony whereof I affix my signature in presence of two witnesses.

WERDEN A. SANDERS.
